UNITED STATES PATENT OFFICE.

JACK THAW, OF BALTIMORE, MARYLAND.

SHOPPING BAG.

Application filed November 15, 1921. Serial No. 515,337.

To all whom it may concern:

Be it known that I, JACK THAW, a citizen of Canada, subject of the King of Great Britain, and resident of Baltimore, Maryland, have invented certain new and useful Improvements in Shopping Bags, of which the following is a full, clear, and exact description.

My improvement relates to shopping bags and has for its object to provide such a device which is neat in appearance and yet is strong and serviceable in use.

Another object of the invention is the formation of the shopping bag of flexible material with certain portions thereof stiffened to prevent folding and creasing of the bag thereby retaining the same in its original shape.

Other objects and advantages of the invention will be apparent from the following description when taken in connection with the accompanying drawings, in which,

Figure 1 is a perspective view of my preferred form of shopping bag.

Figure 2 is a fragmentary end view of the bag, showing certain details of construction.

Figures 3 and 4 are enlarged vertical sectional views taken on lines 3—3 and 4—4 respectively of Figure 1.

Figure 5 is a horizontal section taken on line 5—5 of Figure 1.

Figure 6 is a fragmentary sectional view of a slightly modified form of bag.

Figure 7 is a side view of another form of bag.

Figure 8 is an enlarged fragmentary section taken on line 8—8 of Figure 7.

Figure 9 is a side view of a still further modified form of bag.

Figure 10 is an enlarged sectional detail taken on line 10—10 of Figure 9, and,

Figure 11 is a detail perspective view of a corner of the bag shown in Figures 9 and 10.

Referring to the drawings more in detail, the numeral 1 designates the preferred form of shopping bag which may be made of oilcloth, leather or similar flexible material. In the form shown in Figures 1 to 5 inclusive, the bag is formed of integral side

and bottom walls 2 and 3 respectively, and end walls 4. The side walls 2 of the bag terminate below the upper ends of the end walls 4 and have secured to the upper edges thereof, by stitching or the like, the facing strips 5 and 6 which are also secured to the side edges of the end walls 4, 4. The upper

edges of cooperating facing strips 5 and 6 are connected by a binding strip 7, thereby forming a completely enclosed pocket. In order that the bag will retain its original shape I have provided resilient stiffening strips 8, preferably of metal, which are located in these pockets; slits 9 being formed in the inner facing strips for the purpose of introducing the stiffening strips 8.

To reinforce the bag, straps 10 are provided having their edges covered by the binding 11. These straps 10 extend vertically of the side walls of the bag and under the bottom thereof, and are secured to the bag by rows of stitching. Washer grommets 12 also secure the straps 10 to the bag by passing through the straps and through the side walls of the bag. These washer grommets aid in holding up the bottom portion of the bag. Other washer grommets 13 extend through the facing strips 5 and 6 and the ends of the straps 10 fastening these parts together and also forming means by which the handles 14 may be attached to the bag. By means of this construction of straps, washer grommets and handles, the weight of the contents of the bag is transmitted directly to the handles and thereby relieves the strain on the bag.

The form of the invention shown in Figure 6 is identical with that shown in Figures 1 to 5 inclusive, with the exception that the inner facing strip 6 is omitted and the wall 2' extends to the extreme upper edge 90 of the bag, as shown at 2'', thereby taking the place of the inner facing strip and forming with the outer facing strip 5 the pocket for the stiffening strip 8.

In the modified form of the invention shown in Figures 7 and 8 I have provided the bag 20 with rivets 21 for securing the straps 22 to the side walls thereof, and other rivets 23 for securing the straps to the bottom of the bag. These straps, on which the binding 11 is omitted, are also secured to the bag by rows of stitching as in the previously described form. In other respects the bag shown in Figures 7 and 8 is identical with that shown in Figure 6.

Figures 9, 10 and 11 show a still further modified form of bag 30 which is identical with the construction shown in Figure 6, except that the separate end walls are omitted and the side walls 31 and 32 are connected by the binding strips 33.

In accordance with the patent statutes I

have described what I now believe to be the best embodiment of the invention, but I do not wish to be understood thereby as limiting myself or the scope of my invention, as many changes and modifications may be made without departing from the spirit of the invention, and all such I aim to include in the scope of the appended claims.

What I claim as new and desire to secure 10 by Letters Patent is:

1. A shopping bag including flexible side and bottom walls, straps attached to the side walls of the bag by rows of stitching or the like, the ends of said straps terminating 15 at the mouth of the bag, grommets passing through the respective strap ends and the side walls of the bag, and handles having their ends secured in said grommets.
2. A shopping bag including flexible side 20 and bottom walls, straps attached to the side and bottom walls of the bag by rows of stitching or the like, grommets located adjacent the upper edge of the bag and securing the ends of the straps to the bag body, 25 and handles attached to said grommets.
3. A shopping bag formed of flexible material, a facing strip attached to the bag adjacent the top thereof forming a pocket, one of the walls of the pocket being provided 30 with a slit, and a strip of resilient material in said pocket.

4. A collapsible shopping bag substantially rectangular in cross-section and including side and bottom walls formed of flexible material, flexible end walls secured to 35 the side walls, facing strips secured to each of the side walls adjacent the top thereof, thereby forming pockets, and a rectilinear strip of stiffening material positioned in one of said pockets.

5. A shopping bag including side and bottom walls formed of flexible material, flexible end walls secured to the side walls, facing strips secured to each of the side walls thereby forming pockets, and a strip 45 of resilient material positioned in one of said pockets.

6. A shopping bag comprising integral side and bottom walls formed of flexible material, flexible end walls secured to the side 50 walls, facing strips having their lower edges secured to the inner and outer sides of the side walls at the upper ends thereof, thereby forming pockets, the ends of the facing strips being secured to the end walls, straps 55 attached to the side and bottom walls and to the upper edges of the facing strips, strips of resilient material positioned in said pockets, grommets securing the strap ends to the facing strips, and handles attached to 60 said grommets.

JACK THAW.
